N. C. DE LOSS

LOOSE LEAF BINDER

Filed April 17, 1926

Norman Clayburgh Velos INVENTOR.
BY Frank W. Stough
HIS ATTORNEY.

UNITED STATES PATENT OFFICE.

NORMAN CLAYBAUGH DE LOSS, OF CLEVELAND HEIGHTS, OHIO.

LOOSE-LEAF BINDER.

Application filed April 17, 1926. Serial No. 102,800.

My invention relates to an improved loose leaf binder and more particularly it relates to an expandible loose leaf binder.

One of the objects of my invention is to provide an improved loose leaf binder which is automatically expandible.

Another object of my invention is to provide an improved loose leaf binder which is automatically expandible and provided with a protective back upon which data of the contents of the binder may be placed.

Another object of my invention is to provide an extensible loose leaf binder in which there are no undesirable projections to prevent the binder from being stacked or arranged in the files occupying but a minimum amount of space.

Other objects and advantages of my invention and the invention itself will be apparent by reference to the accompanying drawings wherein,

Fig. 1 shows a fragmentary longitudinal sectional view of an embodiment of my improved binder contracted;

Fig. 2 shows a similar view of the embodiment expanded;

Fig. 3 shows a fragmentary horizontal sectional view on the line 3—3 of Fig. 1, looking in the direction of the arrows, and showing one of the spring drums in section and one in elevation;

Fig. 4 shows a vertical sectional view of my invention taken on the line 4—4 of Fig. 1, looking in the direction of the arrows;

Fig. 5 shows a horizontal sectional view on the line 5—5 of Fig. 1, looking in the direction of the arrows;

Fig. 6 shows a vertical sectional view of the back enlarged twice the size of Fig. 1;

Fig. 7 shows a fragmentary longitudinal sectional view of the embodiment of Fig. 1 showing one cover open;

Fig. 8 shows a detail view of one means of fastening the elastic strip and extension strips; and

Fig. 9 shows a modification of the embodiments of Figs. 1 to 8.

Referring to Figs. 1 to 8 of the drawings wherein like reference characters designate like parts throughout the drawings and specification, at 1 and 2, I show covers of my loose leaf binder having recesses 3, 4, 5 and 6 extending from the inner surfaces preferably disposed in the ends adjacent a back 12 and formed by the U-shaped plates 56 and

57, secured to the reduced portions 90 and 91 of the covers, and adapted to house spring drums 11, 13, 14 and 15. The spring drums are preferably constructed and operate similar to the conventional typewriter carriage return spring drums and of substantially the same tension, and are adapted to rotate in suitable bearing rods 60, 61, 62 and 63 anchored in the U-shaped plates 56 and 57. One end of the spring 27 is secured to one of the bearing rods 60, and is coiled about the same, the opposite end of the spring is then riveted to the interior wall of the casing 11, which is adapted to rotate on the bearing rod. A pair of binder straps 7 and 8 are employed to hold the covers together, by preferably riveting their ends to the periphery of the spring drum casings, and retain leaves 75 in the binder by passing through a pair of holes 24 formed in the inner ends of each of the leaves.

Two spring drum casings are carried by each cover, two in the recess formed by each of the U-shaped plates 56 and 57, the spring drum casings and associated parts being preferably identical in construction, but one pair of spring drums and one strap will be described in detail.

One end of the binder strap 7 is preferably riveted at 16 to the spring drum casing 11 and is wrapped about substantially the entire periphery thereof and extends tangentially therefrom. The opposite end of the strap is secured in a like manner at 17 to the spring drum casing 13 and is also wrapped about the casing, the two spring drums causing a tension to be exerted on the strap in opposite directions tending to continually draw the covers and their associated parts together. The spring drum casings are mounted to rotate on vertical axes in the recesses. The side of the strap 7 is disposed vertically when it leaves the spring drum casing and passes over a pair of rods 19 and 20 secured in the recess 3 adjacent a preferably rectangular opening 21 provided in the lower wall of the U-shaped plate 56, the longer sides of the opening being parallel to the rear wall of the binder through which the strap enters after passing over the rods. The rods are arranged at right angles each to the other so that when the strap passes, first over 19 and then over 20, the side of the strap, which was formerly disposed on a vertical plane, will now be turned at right angles to

its initial position to enable it to slide in and out of the rectangular opening in the lower wall in the U-shaped plate. The width of the strap is presented at right angles to the 5 slots 21 provided in the U-shaped plates 56 and 57 carried by the binder covers 1 and 2 and the slits 25 in the leaves 75 to retain the leaves from accidental displacement.

In a like manner, as above described, the 10 strap extends down through a rectangular opening 28 provided in the upper wall of the lower U-shaped plate and passes over a pair of rods 29 and 30, arranged at right angles to each other and anchored in the U-shaped 15 plate 57 adjacent the rectangular opening and is secured to the spring drum casing 13 preferably by rivets 17, and partly surrounds the same in a manner identical with the upper end thereof, as heretofore described 20 at 11 and 16, respectively.

My improved expandible back, generally indicated by the numeral 12, preferably comprises a hollow plate 40, supported by a pair of extension webs 41 and 42, secured at their 25 inner ends to elastic strips 44 and 43 adjacent to each other at the interior of the hollow plate. The opposite ends of the elastic strips are secured to the interior wall of the plate 40 by rivets 45 and 46 or the like. The opposite 30 horizontally extending ends 72 and 73 of the extension webs project from openings in the upper and lower ends of the hollow plate and are disposed parallel to and secured to the U-shaped plates 56 and 57 at 50 and 51, 35 by rivets 96 or the like. The extension webs and elastic strips may be secured together in any suitable manner preferably by means of stitches as 48 and 49. One preferred manner of stitching of these parts together is shown 40 in Fig. 8 of the drawings wherein the extension strips are provided with reenforcing strips 81. The elastic strips and extension webs are preferably arranged parallel to each other in the interior 53 of the plate and at 45 substantial right angles to the horizontally extending portions of the extension webs. Slots 54 and 55 provided in the ends of the hollow plate permit the extension webs to slide back and forth therein to enable the 50 binder to expand automatically as additional leaves are placed on the strips in the same.

The edges of the hollow plate 40 are preferably rounded at 70 and 71 to prevent any undesirable cutting of the extension webs when 55 they pass through the openings 54 and 55 and over the rounded ends of the hollow plate when expanding. This arrangement further permits the extension webs to be extended with a minimum amount of frictional resistance being set up between the same and the ends of the hollow plate, and more efficiently permits the binder to be expanded.

Referring to Fig. 9 of the drawings, I have 60 illustrated a modification of the straps and rods of the foregoing figures and description.

At 35 I show a strap of circular cross section which is secured to the spring drum casing 11' by rivets 16', or the like, and partly surrounds the casing and then tangentially leaves the same and passes over a rod 20' 70 anchored at its ends to the U-shaped plates 56', one rod only being necessary in this embodiment by virtue of the circular form of the strap. The strap after passing over the rod and curving around the same will enter a circular hole 38 disposed in the lower wall of the U-shaped plate adjacent the rod and slightly larger in diameter than the diameter of the strap, and extends to and enters a circular hole 82 provided in the upper wall of the lower 80 U-shaped plate 57'. The strap then passes over the rod 29' and partly around the same on to the casing 13' and is secured preferably by rivets 17' to the outer periphery of the casing. 85

The circular strap employed in this embodiment of my invention has the economic advantage of dispensing with the use of one rod in each recess and further reduces the wear and twisting strain on the straps. 90

The extension webs in length are each preferably one half the minimum thickness of the binder, and the elastic strips are sufficiently resilient to be stretched to enable the binder to be automatically expanded more than double its minimum thickness. When it is desired to insert a leaf in the binder, the covers are automatically separated by exerting a slight force against the tension of the springs and elastic strips and the slits 25 in the leaves 100 are passed over the straps so that the holes 24 surround the straps. When a leaf is to be removed from the binder the cover is swung open as shown in Fig. 7 of the drawings and the leaf withdrawn by passing the straps 105 through the slits 25 in the leaves.

A binder constructed in the manner set forth in the foregoing dispenses with any manual adjustment of the parts permitting the binder to expand or contract automatically 110 by virtue of the springs and straps. The back is also expanded or contracted automatically, the extension portions thereof telescoping into the hollow plate of the back in contracted position and extending out of the 115 same in expanded position to afford a protective back for the binder leaves when the same is either in expanded or contracted position. Dust or dirt is less likely to enter the binder provided with my improved protective back 120 when the same remains in its filing place a period of time.

When the binder has been expanded substantially twice its normal thickness by virtue of filing a plurality of leaves therein, the 125 data concerning the contents of the binder is placed on the back. The binder may then be readily filed on filing shelves when it has been filled with leaves without offering any undesirable projections so that the binder 130

will occupy but a minimum amount of space. The data on the back is at all times presented to view saving considerable time in removing from and returning the same to the filing shelves.

5 The straps are of sufficient length to permit the covers of the binders to be swung into full open position when the same is expanded to its maximum thickness to permit leaves to 10 be inserted or removed. The tension of the springs is great enough to hold the covers in closed position at all times, manual force being necessary in order to open the binder. The straps and extension strips function to 15 together to retain the binder in assembled and compact relationship.

Having thus described my invention I am aware that numerous and extensive departures may be made from the embodiments 20 herein illustrated and described, but without departing from the spirit of my invention.

What I claim is:—

1. In an automatic expanding loose leaf 25 binder comprising top and bottom covers, binder straps, a back, said back comprising a rigid portion and a flexible extensible portion, and means carried by each of the covers to pull the covers toward each other by the 30 agency of the binder straps.

2. A loose leaf binder comprising top and bottom covers, binder straps, a back, said back having flexible strips and elastic strips secured to each other at one end in pairs, 35 the outer end of each flexible strip secured to one of the covers, the other end of each elastic strip secured to the back, and means carried by said covers to exert a pull on the covers towards each other through the agency 40 of said binder straps.

3. In a loose leaf binder, the combination with a pair of covers, of resilient means connected with the covers to draw them toward each other and a back carried by said covers, 45 said back having a rigid portion and extensible portions.

4. In a loose leaf binder, a pair of relatively movable covers, a plurality of drums and a resilient means connected to each of 50 the covers, said means comprising a plurality of flat flexible binder straps, each connected to a pair of said drums, retractile springs in said drums, said drums journaled in the binder covers, and said springs exerting a 55 constant pull upon the binder straps drawing the covers towards each other.

5. In a loose leaf binder, a pair of relatively movable covers, a plurality of drums and a resilient means connected to each of 60 the covers, said means comprising a plurality of flat flexible binder straps, each connected to a pair of said drums, retractile springs in said drums, said drums journaled in the binder covers and said springs exerting a 65 constant pull upon the binder straps draw-

ing the covers towards each other, and a back carried by said covers, said back having a rigid portion and an extensible portion.

6. In a loose leaf binder, a pair of relatively movable covers, said covers each comprising a 70 solid portion and a hollow portion, and resilient means mounted in the hollow portion of each of said covers, and flat flexible binder straps connected to said means, said resilient means adapted to constantly exert a pull on 75 the straps to draw the covers towards each other, and a back carried by said covers, said back having a rigid portion and an extensible portion.

7. In a loose leaf binder, a pair of relatively 80 movable covers, said covers each comprising a solid portion and a hollow portion, resilient means mounted in the hollow portion of each of said covers, flat flexible binder straps connected to said means, said resilient means 85 adapted to constantly exert a pull on the straps to draw the covers towards each other, and an extensible back, said back comprising a rigid portion, a pair of flexible strips and a pair of elastic strips secured to each other, 90 said flexible strips secured to the binder covers and said elastic strips secured to the rigid portion of the back.

8. In a loose leaf binder, a pair of relatively 95 movable covers, each comprising a solid portion and a hollow portion, a plurality of spring drums rotatably mounted in the hollow portions of the covers, a plurality of flat flexible binder straps having their ends secured to the said drums, and adapted to exert a pull upon the covers to constantly draw them towards each other, and means comprising a plurality of guide pins disposed at right angles to each other about which the straps extend, adapted to twist the straps at right- 100 angles intermediate their ends.

9. In a loose leaf binder, a pair of relatively 110 movable covers, each comprising a solid portion and a hollow portion, a plurality of spring drums rotatably mounted in the hollow portions of the covers, a plurality of flat flexible binder straps having their ends secured to the said drums, and adapted to exert a pull upon the covers to constantly draw them towards each other, and means comprising a plurality of guide pins disposed at right angles to each other about which the straps extend, adapted to twist the straps at right angles intermediate their ends, and a 115 back carried by said covers, said back having a rigid portion and an extensible portion.

10. In a loose leaf binder, a pair of relatively 125 movable covers, each comprising a solid portion and a hollow portion, a plurality of spring drums rotatably mounted in the hollow portions of the covers, a plurality of flat flexible binder straps having their ends secured to the said drums, and adapted to exert a pull upon the covers to constantly draw them towards each other, and guide 130

means disposed within the hollow portion of the covers about which the straps extend adapted to twist the straps at right angles intermediate their ends.

5 11. In a loose leaf binder, a pair of relatively movable binder covers, retractile spring means carried in rotatable drums journaled

in the covers and binder straps connected to said drums and adapted to draw the covers towards each other by virtue of the retractility of said spring means. ¹⁰

In testimony whereof I hereunto affix my signature this 27th day of March, 1926.

NORMAN CLAYBAUGH DE LOSS.
